UNITED STATES PATENT OFFICE

JOHN F. DORNFELD, OF SAN DIEGO, CALIFORNIA

DESIGN FOR A GRAVE MARKER

Application filed September 3, 1931. Serial No. 41,011. Term of patent 7 years.

To all whom it may concern:

Be it known that I, JOHN F. DORNFELD, a citizen of the United States, residing at San Diego, in the county of San Diego and State of California, have invented a new, original, and ornamental Design for a Grave Marker, of which the following is a specification, reference being had to the accompanying drawing, forming a part thereof, in which the figure is a top or plan view of my new design

for grave marker and it is a slab of conventional thickness, and its reverse side is plain.

I claim:

The ornamental design for a grave marker substantially as shown and described.

In testimony whereof, I have hereunto set my hand at San Diego, California, this 27th day of August, 1931.

JOHN F. DORNFELD.
